UNITED STATES PATENT OFFICE

167,687

CLIP

Marvin I. Glass, Chicago, Ill., assignor to H. Fishlove & Co., Chicago, Ill., a corporation of Illinois

Application February 20, 1952, Serial No. 18,606

Term of patent 14 years

(Cl. D17—10)

To all whom it may concern:

Be it known that I, Marvin I. Glass, a citizen of the United States, residing at Chicago, county of Cook, and State of Illinois, have invented a new, original, and ornamental Design for a Clip, of which the following is a specification, reference being had to the accompanying drawing, forming a part hereof.

Fig. 1 is a perspective view of a clip with the conventional fastener illustrated in broken lines.

Fig. 2 is a front view thereof, and

Fig. 3 is a rear view thereof.

I claim:

The ornamental design for a clip, as shown and described.

MARVIN I. GLASS.
